UNITED STATES PATENT OFFICE.

DANIEL O'HARA, OF WALTHAM, MASSACHUSETTS.

WATCH-CASE.

SPECIFICATION forming part of Letters Patent No. 309,158, dated December 9, 1884.

Application filed June 7, 1884. (Model.)

To all whom it may concern:

Be it known that I, DANIEL O'HARA, of Waltham, in the county of Middlesex and State of Massachusetts, have invented certain new and useful Improvements in Watch-Cases, 5 of which the following is a full, clear, and exact description.

This invention consists in certain improvements in watch-cases in which the movement-ring is provided with one or more risers constructed to project from and overlap one or both sides of the central shell.

It further consists in a watch-case in which the movement-ring is provided with one or 15 more risers constructed to project from and overlap one or both sides of the central shell, in combination with suitable devices for connecting the parts together and to prevent their rotation, all as will be hereinafter fully described.

The figures of the accompanying plate of drawings, forming a part of this specification, illustrate the present invention, and they are all in a similarly enlarged scale.

25 Figure 1 is in part a central transverse section and in part an edge view of a watch-case with the movement removed. Figs. 2 to 13, both inclusive, are sectional views at one side only of a watch-case, and they are all in illustration of the construction of the movement ring or band and its attachment to the annulus or central shell or body in accordance with the several features of this invention; and Fig. 30 14 is a similar view to Fig. 1, illustrating detail changes of construction of the movement ring or band, without departing, however, from the principles of this invention.

In the drawings, A is the band or movement to contain the watch-movement. B is the central shell or annulus or body. C is the front bezel-ring, and D its crystal. E is the back bezel-ring, and F its crystal. G is the front cap or plate. H is the back cap or plate.

The movement band or ring A interiorly is 45 adapted in any of the usual ways, or in any other suitable way, for receiving and securing the watch-movement. (Not represented in the drawings.) This ring A exteriorly is surrounded by the annulus or central shell, B, preferably made with a recess or chamber, J; but it may be made solid, or nearly so, using a baser metal for the inner portion thereof,

and for its exposed sides or surfaces silver, gold, or other suitable metal or material.

The annulus and movement-ring B A may 55 be made either of the same or of different kinds of metal or other material, and they are made separate and distinct from each other, the ring A being provided with a riser, K L, at the front and back sides, *ab*, of the annulus B, for the attachment at the front side of the front bezel-ring, C, and at the back side of a back bezel-ring, E, Fig. 1, or of a back cap or plate, H, Fig. 14.

The risers K L of the movement-ring A may 65 both be made of one piece therewith, Figs. 8, 12, and 13, or either or both of them made separate and distinct from the ring, and also from the annulus and attached to the ring in any suitable manner—as, for instance, by 70 screwing it or them upon the ring, or by other means of fastening—and this construction of the riser separate from and attached to the ring is shown in Figs. 1 to 7, both inclusive, Figs. 9 and 14.

75 In Fig. 1 the riser at the front of the annulus is of the ring itself, and the riser at the back of the annulus is made separate from the ring and screwed upon the outside of it, passing by its flange portion *d* into the chamber of 80 the annulus, and the same construction in substance is shown in Figs. 2, 7, and 14.

In Fig. 3 the riser at the front of the annulus is made separate from the ring and attached thereto by screwing it upon the outside 85 of the ring, and the riser L at the back of the annulus is made of the ring itself.

In Fig. 4 the riser at the back of the annulus is made separate from the ring and attached thereto by screwing it upon the outside 90 of the ring, and the riser at the front of the annulus is made of the ring itself and flanged, as at *f*, to lap over and upon the front face or side, *g*, of the annulus.

In Fig. 5 both risers are made separate 95 from the ring, and each attached by screwing it upon the outside thereof.

In Fig. 6 the construction and attachment of the risers are the same as shown in Fig. 4, and which has been described, with this exception, that the attached back riser, L, is further secured by a fastening screw or rivet, *h*, entered into it and the ring.

In Fig. 8 both risers are in one piece with

the ring, as has been before stated, and the front riser provided with a separate ring, *k*, screwed upon the same and against the front side or face, *g*, of the annulus *B*, and thus differing in that respect from the same construction, substantially, of the ring with risers shown in Fig. 12, and also shown in Fig. 13, and also in the further respect from the construction shown in Fig. 12, in that the ring at its back riser, *L*, is fastened to the annulus by a screw or rivet, *l*, passing through it into said annulus, and from the construction shown in Fig. 13, in that the separate ring at the front side of the annulus and the riser at the back side of the annulus are both fastened to the annulus by screws or rivets *m m* passing through said separate ring and said riser into the annulus.

In Fig. 9 the front riser, *K*, is made separate from and screwed upon the ring *A*, and the back riser in two parts, *M N*, one of which is screwed upon the outside of the ring *A*, entering into the chamber *J* of the annulus *B*, and the other, *N*, screwed upon the outside of said part *M* so screwed upon the ring *A*, and this construction differs from that shown in Fig. 14 in these respects, that in Fig. 14 the riser *K* at the front is shown as in one piece with the ring, instead of a separate piece therefrom, as shown in Fig. 9, and the riser *L* at the back, while it is made separate from the ring, is in one piece in lieu of two pieces, as shown in Fig. 9, and resembling in the latter respect the back riser and its attachment shown in Fig. 7.

In Figs. 10 and 11 the front riser is shown as in one piece with the ring *A*, and the back riser as in part *O* made of the ring and in part *P* made of the annulus, Fig. 10 showing the back riser in its part *O* made from the ring *A*, wholly surrounded by the part *P* thereof, made from the annulus, and Fig. 11 showing the back riser in its part *O* made from the ring and its part *P* made from the annulus in continuation of each other at the exterior periphery of the riser. In both views, Figs. 10 and 11, a fastening screw or rivet, *h*, is shown as entered into and through the back riser and the annulus.

In all of the constructions of the ring *A* with risers herein particularly described, either one or both of the risers, or the part attached to or on either of them—as, for instance, the flange *f*, Figs. 1, 4, 6, 7, 8, and 13—and not constituting any part of the riser itself for the use to which it is to be applied, laps over or sets against the surface of the central shell or annulus at the side of the annulus at which they are located, and where either or both of the risers so lap over or set against the surface of the annulus, and the overlapping flange *f* at one side is attached to the riser by screwing it thereon, the annulus is secured to the ring, or vice versa, by the confinement thus secured of the annulus between the so overlapping and secured parts of the ring. In case either riser of itself or any

part attached to it does not lap over and against the corresponding side of the annulus, then the ring and annulus must be fastened together in some other manner—as, for instance, by fastening screws or rivets, as shown in Figs. 10, 11, 12, and 13; and, if desired, fastening means of this character may be used even when the risers at both sides lap over and against the sides of the annulus, as shown in Fig. 1.

In Figs. 1 and 14 the riser at the back of the annulus has the back plate or cap screwed to it, and the part of the ring making such riser, and which is screwed upon the ring itself, is a bezel-ring to receive the back crystal, *F*. Again, the front riser receives the front bezel-ring, *C*, and, in addition, in Fig. 1 the case at its front is shown as provided with a front cap or plate, *G*, to be hinged to the annulus at such side, and provided with an opening-spring located in the recess or chamber *J* of the annulus, all as well known.

The annulus and ring construction shown in Figs. 4, 6, 8, 10, 11, 12, and 13, more especially referring to the shoulder at *q* at the front side of the annulus, adapts the annulus for a front cap or plate to be hinged to or snapped upon the annulus, hinging being preferable, the front bezel-ring being attached to the riser *K* at the front of the annulus. In most of the figures both risers *K L* are shown as constructed for the parts which are to be attached to them to be screwed upon them, notably Figs. 1 to 6, both inclusive, Figs. 8, 9, and 14, while in Figs. 7, 10, and 11 the back riser is adapted for the part to be attached to it to be screwed upon it, and the front riser for the part to be attached to it to be snapped over it, and in Figs. 12 and 13 both risers are adapted for the parts to be attached to them to be snapped over them, or, in lieu thereof, they may be hinged.

If the movement-ring is made in two or more parts screwed together, their screw-threads, as also the screw-thread by which the back cap or plate or front bezel or other part of the case is attached to the movement, should run in the opposite direction, which obviously would prevent the possibility of an accidental separation of the movement-ring and annulus as the said back cap or said bezel or other part is being removed.

The risers *K L* may be secured to the movement-ring *A* in other ways than by screwing them upon the ring—as, for instance, by hinge, snap, or in any other of the common or suitable ways proper in making watch-cases or other like articles. Again, the risers may be fastened to the ring by screws or rivets, or by solder or other means, in addition to the particular construction of them and the ring. The risers, if attached by solder or other equivalent way, obviously become part or in one piece, as it were, with the movement-ring—that is, substantially so—and consequently in this description all such portions of it speaking of a riser being made in one piece with

the ring are used in their broadest sense, meaning to include the risers when made separate from the ring, but permanently attached thereto by solder or otherwise, as above indicated.

5 A watch-case of the present improved construction can be most economically made, as it then would require but very little precious metal, and that for the central shell or annulus only, which can be a mere shell, cheaper or 10 baser metals—such as albata, nickel, brass, or other kind—being used for the movement-ring and the construction of risers described.

The attachment of the central shell or annulus and movement-ring can be made the more 15 secure, if desired, by passing the screws which are to fasten the case-springs in the chamber of the annulus through either one or both risers and the annulus. Bases of the described construction may be made very heavy, and at 20 the same time use but a small proportion of precious metal.

It is preferable to attach the several parts of the watch-case together, or at least all such parts as do not require to be opened for the 25 ordinary daily use of the watch, by screwing them into place, for the reason that the joints

can be thus made lighter and closer and more capable of preventing the passage of dust, air, or moisture to the movement.

Having thus described my invention, what I 30 claim, and desire to secure by Letters Patent, is—

1. A watch-case in which the movement-ring is provided with one or more risers constructed to project from and overlap one or 35 both sides of a central shell, substantially as described.

2. A watch-case in which the movement-ring is provided with one or more risers constructed to project from and overlap one or 40 both sides of a central shell, in combination with suitable devices for connecting the parts together and to prevent their rotation, substantially as described.

In testimony whereof I have hereunto set my 45 hand in the presence of two subscribing witnesses.

DANIEL O'HARA.
